UNITED STATES PATENT OFFICE

ROMAN TRECHCINSKI, OF WARSAW, POLAND, ASSIGNOR TO TELEFONAKTIEBOLAGET
L. M. ERICSSON, OF STOCKHOLM, SWEDEN, A COMPANY OF SWEDEN

AUTOMATIC AND SEMIAUTOMATIC TELEPHONE SYSTEM

Application filed April 28, 1928, Serial No. 273,750, and in Sweden May 2, 1927.

The object of the present invention is to provide inter-office traffic between automatic telephone exchanges of the kind in which the selectors are set by means of current impulses sent in a forward direction in synchronism with the impulse sending from the subscriber's station, on the one hand, and such exchanges in which the selectors are set by means of revertive or back-impulses, controlled by a register, on the other hand. When establishing telephone connections from subscribers connected to exchanges of the first mentioned type, to subscribers appertaining to exchanges of the latter type, it is necessary to provide the junction lines between said exchanges with registers which are able to receive the impulses sent from the first exchange and to control the establishment of the telephone connection in the latter exchange. Assuming that the calling subscriber must be able to send the current impulses quite independent of the switching operations in the exchanges, the arrangement should be disposed in such a manner that a register always is standing by, ready to receive the impulses as soon as a junction line is engaged. This problem can be solved in the easiest manner by providing each junction line with a separate register. As a register, however, is a comparatively expensive apparatus and, furthermore, is in use only during the establishment of the telephone connection, it is desirable to use a smaller number of registers which are common to a larger number of junction lines. This is made possible according to the present invention by arranging those registers which are common to one group of junction lines in such a manner that they are connected automatically immediately after the completed setting of the selectors, to another line which is free at that moment and to which no register is already connected. At the same time a junction line which is not engaged by a telephone connection is marked as free for such connection only after a disengaged register has been connected to this line.

The invention will be further described with reference to the attached drawing which shows partially a telephone connection comprising a circuit arrangement according to the invention.

Those parts of the telephone connection which appertain to different exchanges are separated by a dashed and dotted line L_1 . On the left hand side of this line there is shown a group selector GV_1 appertaining to an exchange which, by way of example, can be built according to the known Strowger system, see for instance the United States Patent 815,176 Keith and Erickson March 13, 1906 whereas those parts which are placed on the right hand side of said line appertain to an exchange of such a kind in which the telephone connections are established by the intermediate of a register, see for instance the United States Patent 1,580,321 Palmgren April 13, 1926. The junction line a, b, c between these two stations terminates in the latter exchange in another group selector GV_2 . The registers can be of any suitable type for instance of the type described in the United States Patent No. 1,580,321. On the drawing there is shown inside the dashed and dotted line L_2 only those parts of such a register which are necessary for explaining the operation of the system. Each register is provided with a searcher the parts of which are shown inside a dashed and dotted line L_3 . Said searcher can be of the machine driven type and is provided with a clutch magnet S for coupling the shaft of the searcher to a continuously rotating shaft. The shaft of the searcher is provided with six contact arms which are intended to make contact with certain contacts in a corresponding number of contact rows A, B, C, D, E, F in such a manner that the two opposite contacts in each separate contact position are electrically connected through the corresponding contact arm.

A free register connects itself automatically to a free junction line in the following manner. All junction lines which are not engaged by a conversation and to which a register is not already connected, are marked as free in the searchers thereby that the relay DR_4 is deenergized, the corresponding contact in the contact row F being connected to the negative pole of the battery over a re-

sistance R_1 . As long as the searcher moves over contacts which are not marked in such a manner, the clutch magnet S remains energized over a contact of a testing relay RR_1 .

5 When the searcher finds a junction line which is marked as free, the relay RR_1 is energized over the circuit 1 and the said contact is interrupted and the searcher stops. During the movement of the searcher also a relay

10 RR_2 has been energized over the same contact of the relay RR_1 . When the relay RR_2 is de-energized, a circuit 2 is closed through a relay DR_1 a relay GR and a contact k_1 of a sequence switch appertaining to the group

15 selector GV_2 . The relay GR locks itself over a contact 3 and the relay DR_1 marks the junction line as free at the group selector GV_1 by disconnecting the c -wire from the battery. Previously the junction line had been marked

20 as engaged because the c -wire was connected to the negative pole of the battery over a resistance R_2 . The junction line is thus now ready to receive a call. During the lapse of time when the register remains connected to

25 the junction line, the latter is marked as engaged for other registers by the drop of voltage in the resistance R_1 which is sufficient to prevent the excitation of another testing relay which is connected into circuit in parallel

30 with the relay RR_1 .

The connection to a junction line which is marked as free, through the group selector GV_1 is established in a manner known per se. After the contact arms of the group selector

35 have been raised to that contact row to which the junction lines in question are connected the searching of a free trunk line is effected by turning the contact arms. The turning movement is started by a current impulse

40 through the winding SL in a magnet SPM of a sequence switch. Then a rotary magnet DM is connected into an impulse circuit containing an interrupter UR . If the first junction line is engaged the magnet SPM remains en-

45 ergized over a circuit 4 which is not interrupted until when the selector finds a free junction line. When the magnet SPM is de-energized, the arm SR of the sequence switch is moved to its third position, the junction line

50 being thus marked as engaged for the second group selector GV_1 as the c -wire is then connected to the negative pole of the battery through a release relay SR and a contact 5 which was closed when the selector left the

55 normal position.

The following current impulses which are sent over the a -branch of the junction line actuate a relay DR_2 which controls an impulse circuit 6 containing an impulse relay

60 RR_3 at the register. The register is thereby set in accordance with the impulses sent. The completion of the telephone connection takes place under the control of the register in a manner known per se. After completed connection the register is returned to the normal

position. During the return period the contact 7 of the register is interrupted while another contact 8 remains closed. Then a circuit 9 is closed through a relay DR_3 which is energized and in turn closes a circuit 10 for a relay DR_4 . The latter relay marks the junction line as engaged for the registers. As long as the relay DR_3 is operative the relays DR_1 and GR are energized over a contact 13 independent of the searcher. The register sender is now started and connects the register in the above described manner to another junction line. When the relay DR_3 was energized the two windings AL , BL of a relay DR_5 were connected into the line circuit, which relay is now energized and connects the relay DR_3 into a retaining circuit over the contacts 11 and 12. When the line circuit is interrupted after a completed conversation the restoring magnet SR receives a current impulse over the circuit 14 and the telephone connection is interrupted in known manner. The circuit for the relay DR_3 is then interrupted at the contact 12 whereupon also the relays DR_4 , DR_1 and GR are de-energized.

I claim:

1. In a telephone system the combination of subscribers' lines, junction lines, means for connecting a calling subscriber's line to a disengaged junction line, automatic switches for further extending the telephone connection from said junction line, registers for controlling the setting of said switches, automatic switching means for connecting an idle register to a junction line, and means under

95

100

the control of a register for causing this register to be automatically connected to a disengaged junction immediately upon the register being set free for other connections.

2. In a telephone system the combination of subscribers' lines, junction lines, means for connecting a calling subscriber's line to a disengaged junction line, automatic switches for further extending the telephone connection from said junction line, registers for controlling the setting of said switches, automatic switching means for connecting an idle register to a junction line, means under the control of a register for causing this register to be automatically connected to a disengaged junction immediately upon the register being set free for other connections, and means under

110

115

120

125

130

3. In a telephone system the combination of subscribers' lines, junction lines, selecting means for selecting a disengaged junction line, means for establishing connection between a calling subscriber's line and a disengaged junction line, means for marking a junction line as non-accessible to said selecting means when there is no register connected to the junction line, automatic switches

for further extending the telephone connection from said junction line, registers for controlling the setting of said automatic switches, automatic switching means for connecting an idle register to a junction line, means under the control of a register for causing this register to be automatically connected to a disengaged junction, immediately upon the register being set free for other connections, and means under the control of a register for marking the junction as accessible to said selecting means upon a register being connected up to said junction line.

15 In testimony whereof I affix my signature.

ROMAN TRECHCINSKI.
